United States Patent

Des. 241,499
Patented Sept. 21, 1976

241,499

FOOT-OPERATED RECEPTACLE

William B. Raftery, Winchester, Va., assignor to Rubber-maid Commercial Products Inc., Winchester, Va.

Filed Mar. 25, 1975, Ser. No. 561,792

Term of patent 14 years

Int. Cl. D7—07

U.S. Cl. D7—195

FIG. 1

FIG. 2

FIG. 3

FIG. 1 is a perspective view of a foot-operated receptacle in closed position showing my new design.

FIG. 2 is a left side elevational view thereof.

FIG. 3 is a front elevational view thereof.

FIG. 4 is a rear elevational view thereof.

FIG. 5 is a perspective view thereof with the cover raised to full open position.

The bottom surface of the receptacle is substantially flat.

I claim:

The ornamental design for a foot-operated receptacle, as shown and described.
